UNITED STATES PATENT OFFICE.

LLOYD B. SMITH, OF TOPEKA, KANSAS.

DESIGN FOR A BRIDGE.

47,171.

Specification for Design.

Patented Mar. 30, 1915.

Application filed June 15, 1914. Serial No. 845,318. Term of patent 14 years.

To all whom it may concern:

Be it known that I, LLOYD B. SMITH, a citizen of the United States, residing at Topeka, in the county of Shawnee and State of Kansas, have invented a new, original, and ornamental Design for Bridges, of which the following is a specification, reference being had to the accompanying drawing, forming part hereof.

The single figure of the drawing is a perspective drawing of a bridge, showing my new design.

This design is for a bridge comprising a plurality of arches supported on piers and having an overhanging or cantaliver sidewalk, this overhanging or cantaliver sidewalk being supported by a plurality of

brackets arranged in separated groups, each group of brackets being substantially over a pier and the adjacent haunches of the arches resting on such pier, and the spaces between the groups of brackets being at the crowns of the arches.

I claim,

The ornamental design for a bridge, as shown and described.

In witness whereof, I have hereunto set my hand at Topeka, Kansas, this eleventh day of June, A. D. one thousand nine hundred and fourteen.

LLOYD B. SMITH.

Witnesses:

PAUL EMERY,
F. E. WELLS.
